United States Patent Office.

PETER FARRELL, OF ALBANY, NEW YORK.

Letters Patent No. 91,219, dated June 15, 1869.

IMPROVED MACHINE FOR FINISHING LEATHER, PAPER, &c.

The Schedule referred to in these Letters Patent and making part of the same.

To all whom it may concern:

Be it known that I, PETER FARRELL, of the city and county of Albany, State of New York, have invented a new and useful Operation in Finishing-Machines for Morocco, Splits, &c., whereby the roller, dummy, flint, or glass used may have its contact with the spring-bed of the table broken instantaneously; and I do hereby declare that the following is a full, clear, and exact description thereof, reference being had to the accompanying drawings, making a part of this specification.

Figure 1 is a perspective view of a finishing-machine representing the contact of the roller and spring-table bed broken.

Figure 2 represents a section of device for one of the modes of effecting the breaking of the said contact.

Figure 3 represents a section of another device for the same purpose.

In operating with the finishing-machines now used for finishing morocco, splits, &c., the operator or person has but little or no control over the machine, and consequently cannot care as he should for the piece of morocco or other leather being operated upon, as the roller, glass, or other tool used in the machine cannot be readily removed from contact with the spring-bed on which the pelt is worked. In consequence of this inability on the part of the operator, the weak or jagged parts often catch and cause the pelt to tear.

By my invention, I give the operator an easy and sure mode of breaking the contact of the dummy, roller, glass, or flint with the pelt while being operated upon, and of throwing it again in contact.

This I may do in several ways: first, by causing the spring-bed, on which the pelt is placed, to fall at one end by means of a handled tumbler, hinged to the frame of the table, which can be thrown down in an instant; or by a duplication of the same, connected by a rod; or by knuckle-joint levers; or by a tumbler or knuckle-joint levers, operating against the lower side of the spring-plank above; or by cams or eccentrics, arranged to operate in the same manner as the tumblers or levers, placed so as to effect the same with either the spring-bed or the spring-plank.

To enable others skilled in the art to make and use the device, or its several modifications by which I effect the breaking of the said contact of the roller, dummy, or other tool used with the spring-table bed, I will proceed to describe my invention, in reference to the accompanying drawings, and their letters of reference, the same letters indicating similar parts.

A, fig. 1, represents any suitable frame, or it may be the sides and ceiling of a room, in which is fixed a part of the apparatus used in this invention.

B, figs. 1 and 2, represents a table, placed under the pitman C, which holds and works the roller s, or

dummy, glass, or other tool to be used to operate upon the pelt, leather, or paper which is to be worked, which is laid on the table B.

The pitman C, figs. 1, 2, and 3, is hung from above from a spring-plank D, properly secured, at its rear end, to the timbers of the frame A or building.

To give stiffness to the spring-plank D, a screw-cut crank-shaft, a, figs. 1, 2, and 3, is used, by which a greater or less amount of pressure is secured from the said spring-plank.

The pitman C is operated by a second pitman, E, fig. 1, which is worked by a crank, F, or fly-wheel, moved by any suitable motor.

The pitman C, suspended over the table B, works directly over a spring-table bed, n, figs. 1 and 2, which table-bed n is placed in the centre of the table B.

In operating, the pitman C, with its tool s, works over and on the spring-table bed n, from one end of the same to the other, as shown by dotted lines in fig. 2.

While thus operating, the leather or paper is placed on the spring-table bed n, when it is polished by the friction of the roller s, or its equivalent, passing over its face.

If, in the process of polishing, the leather being operated upon be weak or ragged, the roller s is apt to catch and tear, and to prevent this, I break the contact of the roller s, or its equivalent, with the spring-table bed n, on which the leather is worked. This I may do in several ways.

One way is by the means of a tumbler, o, figs. 1 and 2.

This tumbler is made in form as shown, and is hinged to a lower timber, m, of the table, fig. 2, and is provided with a handle, r, by which it may be thrown down, as in fig. 1, or as in fig. 2.

When thrown up, as in fig. 2, the spring-bed n is in position to work, and when thrown down, as in fig. 1, the roller s swings clear of the spring-bed from end to end, and the said roller will not be brought in contact with any leather laid thereon.

An eccentric or lever, properly placed, will secure the same result, or two tumblers, or their equivalents, named, placed at each end under the said spring-bed, and connected by a common jointed rod, that will lower the whole spring-bed, will also effect the same.

When the said contact is broken from below, as in fig. 2, I place a stop, p, under the spring-plank D, figs. 1 and 2.

This stop screws through a timber, q, and may be lowered or raised, as may be desired, and is intended to catch the plank D, and prevent it from falling down and carrying the pitman and its tool s with it when the spring-table bed n is lowered.

Or, again, a tumbler, o', fig. 3, placed to work under the spring-plank D, as in fig. 3, may be used and operated by a shaft, furnished with a suitable pulley, or

its equivalent, not shown, or eccentrics, or jointed levers may be used, and in either of these cases the stop *p* is dispensed with, and the spring-bed of the table is made firm.

These several devices are some of the means by which the breakage of the contact of the roller *s* with the spring-bed is effected, as well as the throwing of the same in contact, at pleasure.

Having described my invention,

What I claim, and desire to secure by Letters Patent, is—

Breaking instantaneously the contact of the roller *s*, or its equivalent tool, with the hinged spring-bed *n*, by means of the hinged tumbler *o*, acting in connection with the stop *p*, or its equivalent, substantially as described, for the purpose set forth.

PETER FARRELL
